James H. Taft

United States Patent Office.

ROYAL C. TAFT, WILLIAM B. WEEDEN, AND JAMES W. TAFT, OF PROVIDENCE, RHODE ISLAND.

Design No. 4,519, dated December 13, 1870.

DESIGN FOR A WOVEN FABRIC.

The Schedule referred to in these Letters Patent and making part of the same.

all whom it may concern:

Be it known that we, ROYAL C. TAFT, WILLIAM WEEDEN, and JAMES W. TAFT, all of the city and town of Providence, in the State of Rhode Island, have originated a new and useful Design for Woven fabrics; and we do hereby declare that the following description, taken in connection with the drawing showing a part of the same, is a full, clear, and exact description and representation thereof.

Figure 1 is a face view of the cloth.

Figure 2 is a view in section.

Our invention consists in the combination of lines and spotted stripes, by combining with the line *c* a broken line, to give a mottled effect to the fabric, whereby a distinctive design is produced.

In the drawing—

A represent stripes made up of parallel lines *a a*,
B alternate stripes of the ground of the fabric

relieved by colored spots; both lines and spots being brought to the surface of the cloth by the process of weaving.

c c are broken lines, combined with the line stripes made up of threads to contrast in color with the stripes and arranged at intervals, as shown.

What we claim as new, and desire to secure by Letters Patent, is—

The design for fancy cassimeres, consisting of the broken lines *c c*, the line stripes *A*, and spotted stripes *B*, substantially as shown and described.

ROYAL C. TAFT.
WM. B. WEEDEN.
JAMES W. TAFT.
